UNITED STATES PATENT OFFICE.

ALPHONSIUS FIEN, OF NEW YORK, N. Y., ASSIGNOR TO S. H. POMEROY COMPANY, INC.,
OF NEW YORK, N. Y., A CORPORATION OF NEW YORK.

METAL WINDOW.

Application filed November 3, 1927. Serial No. 230,755.

This invention relates to the construction of metal window frames and has for its general objects to facilitate the manufacture of such window frames, and the assembling of 5 the same and the window sashes, either in the factory or on the job, to increase the efficiency of such windows in excluding air, to provide for such disposition of the pulley chains by which the sashes are counter-balanced, that they shall not be conspicuous and shall not be liable to contact with draperies, and to strengthen such window frames so they will better resist distortion or breakage 10 in the rough handling to which they are sometimes subjected in transportation and in 15 erection on the job. These and other purposes are fulfilled by features of construction to be described hereinafter, with reference to the accompanying drawings in which 20 they are illustrated in a convenient practical form and in which:

Figure 1 is a view in elevation of a window frame which embodies the several features of the invention, showing one of the jambs, 25 a portion of the head, a portion of the sill, and portions of the two sashes, the jamb and the sashes being broken out to save space, and portions of the jamb being also broken out and shown in section to illustrate details 30 of construction.

Figure 2 is a view in sectional elevation on the plane indicated by the broken line 2—2 of Figure 1.

Figure 3 is a detail view of a portion of the 35 head of the frame and jamb, seen from above, with the cap of the head removed, illustrating particularly the relation of the sash pulleys and pulley housing to the head and jamb.

Figure 4 is a detail view in horizontal section on the plane indicated by the broken line 4—4 of Figure 1.

Figure 5 is a detail view in elevation of the 40 interposed section of the pulley stile.

Figure 6 is a view of the interposed section of the pulley stile in section on the plane indicated by the broken line 6—6 of Figure 5.

Figure 7 is a detail view in section on the

plane indicated by the broken line 7—7 of Figure 2, illustrating particularly the features of construction involved in the connection of each jamb to the sill. 50

Figures 8, 9 and 10 are respectively perspective views of the reinforcing plates at the top, mid-section and bottom of the jamb, 55 on a smaller scale.

Figures 11, 12 and 13 are respectively perspective views, also on a smaller scale, of the upper, middle and lower portions of the pulley stile, the upper and lower portions being 60 shown as broken out to save space.

Figure 14 is a top view of the reinforcing plate in the head, showing the location of slots therein.

Figure 15 is a perspective view of the upper end of the jamb, showing tongues formed thereon. 65

Figure 16 is a detail view, in elevation from the inside, showing the means for interlocking the jamb and the frame head. 70

The complete window frame includes a head, a sill and two jambs which are identical except for reversal. Each jamb *a* may be made of a single sheet of metal, formed to suit the window opening in the wall and to receive within it the counter-balance weights, not shown, for the upper and lower sashes as shown clearly in Figure 4. The edge portions of the sheet of metal which forms the jamb are bent toward each other and again toward the back of the jamb, to form jamb members *a*¹ and *a*², the edges being again bent toward each other, in a plane transverse to the plane of the window, to form flanges, as at *a*³ and *a*⁴, which are spaced apart throughout 75 the vertical height of the frame. The jamb thus formed is stiffened and strengthened and its edge portions maintained in proper spaced relation by three heavy metal reinforcing plates *b*, *c* and *d*, shown respectively in Figures 8, 9 and 10, at the top, mid-section and bottom. Each of these reinforcing plates is shaped to fit against the jamb portions *a*¹ and *a*² on the inside, thus maintaining the edge 80 portions of the jamb against spreading and against compression. The reinforcing plate 85

is shown in Figure 8, which is a perspective view of the reinforcing plate *b* at the top of the jamb. The plate *b* is shaped to fit against the jamb portions *a*¹ and *a*² on the inside, thus maintaining the edge portions of the jamb against spreading and against compression. The reinforcing plate 90

is shown in Figure 9, which is a perspective view of the reinforcing plate *c* at the mid-section of the jamb. The plate *c* is shaped to fit against the jamb portions *a*¹ and *a*² on the inside, thus maintaining the edge 95 portions of the jamb against spreading and against compression. The reinforcing plate

b is formed at its upper edge with tongues *b*¹, *b*² and *b*³ for connection with the head of the frame as hereinafter described, being thereby held from displacement in a vertical direction. The middle reinforcing plate *c* is formed with a middle tenon *c*¹ to which are secured the upper and lower portions of the pulley stile, as hereinafter explained, whereby the middle reinforcing plate *c* is held 10 from displacement in a vertical direction. The bottom reinforcing plate *d* is formed with tongues *d*¹ and *d*², by which it is secured to the sill of the frame.

The pulley stile is formed in three sections 15 *e*, *f* and *g* shown respectively in Figures 11, 12 and 13, each section being formed to fit between the members *a*¹ and *a*² of the jamb and thereby prevent displacement of the edge portions of the jamb members toward each other. It is desirable, in order to maintain 20 exact parallelism of the jamb members, that the opposite edges of each pulley stile portion shall be exactly parallel, and as a matter of convenience in manufacture such exact parallelism of the edges of the pulley stile members can best be obtained by turning up the edges as shown at *g*^x. Each pulley stile member is bent to form three projecting vertical rails *e*¹, *e*², *e*³, *f*¹, *f*², *f*³, and *g*¹, *g*², *g*³. These 25 rails form, between themselves and with the portions *a*¹ and *a*² of the jamb, the grooves which receive the flanges of the upper and lower sashes *i* and *k*, as indicated clearly in Figure 4, and the counter-balance chains, 30 one of which is shown at *l* in Figures 1 and 2. Being received in these channels or grooves the counter-balance chains are less conspicuous than they would be if the pulley stile was not grooved and they are not liable to contact with draperies. It will be observed that 35 the vertical ribs *g*¹ and *g*³ of the lower pulley stile member are wider than the ribs *e*¹, *e*³, *f*¹ and *f*³ of the upper and mid members of the pulley stile, whereby the channel or groove 40 below the meeting rails of the two sashes is just wide enough to receive freely the corresponding flange of the lower sash, thus contributing to the exclusion of air, while the wider channels or grooves formed by the narrower rails *e*¹ and *e*³ of the upper pulley stile member and the mid-section member are wide enough to receive properly the chains *l*.

The upper pulley stile member *e* is secured 45 at its lower end to the reinforcing plate *c* by a screw *e*⁴ which engages at its upper edge, as at *c*⁴ the tenon of the middle reinforcing plate *c*, and in order that this upper pulley stile portion *e* may be removed and replaced when necessary, without requiring the removal 50 or replacement of a screw near the head of the window frame, this pulley stile member is formed at the upper end of the rail *e*² with tongues *e*⁵ and *e*⁶, as shown in Figure 11, to enter slots formed in the soffit of the frame head as hereinafter explained.

The middle pulley stile member *f* is secured to the middle reinforcing plate *c* by a screw *f*⁴ which passes through a hole *f*⁵ in the middle rail *f*² and is threaded into a hole *c*⁶ shown in Figure 9, in the tenon of the reinforcing plate *c*.

The lower pulley stile portion *g* is secured to the middle reinforcing plate *c* by a screw *g*⁴ which passes through a hole in the pulley stile portion and is threaded into a hole *c*⁶ 75 in the tenon *c*¹ of the middle reinforcing plate near its lower end. Another screw *g*⁷ passes through a hole in the middle rail *g*², near its lower end, and is threaded into a hole *d*³ in the reinforcing plate *d*.

The lower end of the lower pulley stile member is formed to fit against the sill.

To afford the proper contact surface of the sashes to prevent the passage of air up or down the grooves of the pulley stile and jamb 85 around the flanges of the sashes, at the ends of the meeting rails, the interposed or middle section *f* of the pulley stile has secured to each of its rails *f*¹, *f*² and *f*³, by tongues *h*¹ and *h*², which respectively enter slots in the 90 pulley stile member, as indicated at *f*⁶ in Figure 12, and lap the end of the pulley stile member, a cap *h*, which forms a socket for the reception of rubbing pads *h* of felt, thus affording a felt bearing for both flanges of each 95 sash and preventing the passage of air.

The soffit *m*¹ of the frame head *m* is grooved as at *m*² to receive the flanges across the top of the upper sash *i*, and within the head, extending from the inner face to the outer face, 100 is a heavy metal reinforcing plate *n* which also forms the base of the housing which supports the sash pulleys *o* over which pass the counterbalance chains *l*. The tongues *b*¹, *b*² and *b*³ of the upper reinforcing plate *b* pass 105 up through slots at *m*³, *m*⁴ and *m*⁵ in the soffit *m*¹ and through slots at *n*¹, *n*² and *n*³ in the reinforcing plate *n* and are bent over upon the reinforcing plate, thereby securing the reinforcing plate *n* rigidly to the frame head. A 110 tongue *a*⁵ of the jamb is also passed up through the slot *m*⁸ and is bent over in a direction opposite to that of the tongue *b*¹. The jamb is also formed with tongues *a*⁶¹ and *a*⁷¹ which are passed up through slots *m*⁶ and 115 *m*⁷ in the inwardly turned edge portion of the soffit *m*⁴ and are bent over toward each other. The jamb is also formed at its outer face with a tongue *a*⁸ which is bent over upon the edge of an extended tongue *m*⁸ of the soffit. At its 120 inner face the soffit is also formed with an extended tongue *m*⁹, the upper edge of which is bent over upon itself as at *m*¹⁰ and is cut out to form two shoulders *m*¹¹ and *m*¹². The inner wall of the jamb is bent over upon the 125 extended tongue *m*⁹ of the soffit and has a tongue *a*⁸¹ which is bent down between the shoulders *m*¹¹ and *m*¹². In this manner the jamb is rigidly secured to the frame head to prevent relative displacement in a vertical di- 130

rection, and it is also secured to the frame head to prevent relative displacement in a horizontal direction.

The jamb is rigidly secured to the sill p in such manner as to prevent relative displacement in a vertical direction and also to prevent relative displacement in a horizontal direction by means generally similar to the means described above for connecting the 10 jamb and the frame head. The inside depending flange p^1 of the sill is turned back upon itself as at p^2 and the turned up portion is cut out to form shoulders p^3 and p^4 . The lower edge of the inside wall a^9 of the jamb is 15 lapped over the lower edge of the depending flange p^1 of the sill and is formed with a tongue a^{10} , which is bent inwardly between the shoulders p^3 and p^4 , so that relative displacement of the jamb and the sill in a horizontal direction is prevented, while at the 20 same time relative displacement in a vertical direction is also prevented.

To make it possible to attach and detach the counter-balance chain to and from the 25 sash readily, there is secured to the upper corner of the sash by some suitable means, such as spot welding, a hook q to be engaged by a link of the chain. It thus becomes possible to attach or detach the chain without 30 removing any part of the frame and without removing the sash from the frame.

The tongues e^5 and e^6 of the upper pulley 35 stile portion are passed up through slots or an L-shaped slot at m^8 in the soffit of the head but are not turned over. Thereby it is possible to slip the upper pulley stile portion into 40 place and secure it in place by the single screw e^4 . It will be observed that only four screws are required to hold the entire pulley stile in place.

It will be understood that not all of the 45 herein described features of the improvements are necessarily embodied in one structure but can be used independently of each other if conditions so require and that various modifications in detail of construction and arrangement can be made without departing from the spirit of the invention except so far as such detail may be made the subject of 50 some of the following claims.

I claim as my invention:

1. In a metal window the combination of a jamb formed of a sheet of metal having its opposed edges spaced apart, a pulley stile seated between the opposed edges of the jamb and formed with vertical rails and grooves to receive the flanges of the sash, the pulley stile comprising an upper section and a lower section with one of the ribs of the upper section narrower than the corresponding rib of the lower section to form a wider groove, a flanged metal sash having its flanges received in the grooves of the pulley stile, and a counterbalance chain connected to the sash and

disposed in said wider groove of the pulley 65 stile.

2. In a metal window the combination of a jamb formed of a sheet of metal having its opposed edges spaced apart, a slotted head, a pulley stile seated between the opposed edges of the jamb and formed in three sections, upper, lower and middle, upper, lower and middle heavy metal reinforcing plates within the jamb, and screws to secure the pulley stile sections to the lower and middle 70 reinforcing plates, the upper pulley stile section having a tongue to enter the slot in the window head to retain it.

3. In a metal window the combination of a jamb formed of a sheet of metal having its opposed edges spaced apart, a pulley stile seated between the opposed edges of the jamb and formed in three sections, upper, lower and middle, each section being formed with vertical rails and grooves to receive the 80 flanges of the sash, and felt pads secured to the middle section of the pulley stile to form bearing surfaces for the flanges of the sashes.

4. In a metal window the combination of a jamb formed of a sheet of metal having its opposed edges spaced apart, a pulley stile seated between the opposed edges of the jamb and formed in three sections, upper, lower and middle, each section being formed with vertical rails and grooves to receive the 85 flanges of the sash, a cap secured to the middle section of the pulley stile to form a socket, and a felt rubbing pad secured in such socket.

5. In a metal window the combination of a jamb formed of a sheet of metal, a slotted 90 sheet metal sill and a heavy metal reinforcing plate fitted to the jamb and formed with a tongue to enter the slot of the sill, the jamb also being formed with a tongue to enter the 100 slot of the sill.

6. In a metal window the combination of a jamb formed of a sheet of metal, a slotted sheet metal sill and a heavy metal reinforcing plate fitted to the jamb and formed with a tongue to enter the slot of the sill, the jamb 110 also being formed with a tongue to enter the slot of the sill, the tongues of the reinforcing plate and the jamb being bent over toward the under side of the sill to secure together the jamb, the reinforcing plate and the sill. 115

7. In a metal window the combination of a jamb formed of a sheet of metal, a slotted sheet metal frame head, and a heavy metal reinforcing plate fitted to the jamb and formed with a tongue to enter the slot of the frame head, the jamb being also formed with a tongue to enter a slot of the frame head. 120

8. In a metal window the combination of a sheet metal sill formed with a depending flange, the edge of the depending flange being turned up and cut out to form opposed shoulders, and a sheet metal jamb fitted to the sill and having its lower end lapped about 125

the lower edge of the sill flange and formed with a tongue disposed between the shoulders of the sill flange.

9. In a metal window the combination of
5 a sheet metal frame head formed with an upwardly extending flange, the upper edge of the flange being turned over and cut out to form opposed shoulders, and a sheet metal

jamb having its upper end lapped about the upper edge of the frame head flange and formed with a tongue disposed between the shoulders of the frame head flange.

This specification signed this 1st day of November, A. D. 1927.

ALPHONSUS FIEN.
